UNITED STATES PATENT OFFICE.

ARTHUR C. PLETZ, OF CINCINNATI, OHIO, ASSIGNOR TO JOHN E. DAVIS, OF CINCINNATI, OHIO.

BUNCH-MAKER'S TABLE.

1,200,019.

Specification of Letters Patent.

Patented Oct. 3, 1916.

Application filed August 5, 1915. Serial No. 43,771.

To all whom it may concern:

Be it known that I, ARTHUR C. PLETZ, a citizen of the United States, residing at Cincinnati, in the county of Hamilton and State of Ohio, have invented new and useful Improvements in Bunch-Makers' Tables, of which the following is a specification.

My invention relates to the art of cigar manufacture and particularly to the means employed in the initial cutting of the leaf and "bunching" of the filling material. These are performed at a table provided with cutting mechanism operated by the cigarmaker to cut the binder-leaf to proper size, and thus begin the operation of bunching; and the cigar is then finished by "wrappers" as a final stage of the manufacture. These initial steps are important; and require not only skill and dexterity, but considerable outlay of physical strength and rapidity of action, especially in team-work where the "bunch-maker" is expected to supply two "wrappers" or "finishers".

The ultimate object of my invention is to relieve the bunch-maker of the chief part of the physical labor involved and to render possible the closer concentration of attention upon the proper utilization, manipulation and "bunching" of the leaf, at the same time speeding the entire operation and improving the product.

To these ends my invention consists in the provision and employment in connection with a bunching table of an easily controllable motor-force to drive cutting devices, utilized in a simple, direct-acting motor-mechanism under instant control of the operator.

In the preferred form of my invention, the mechanism devised consists primarily of a motor-cylinder or cylinders of the reciprocating type, arranged and operating axially parallel with the face of the table, with cutting disks carried directly upon and operated by the piston rod or rods; and with a suitable valve for directing and controlling the travel of the pistons simultaneously, and with simplified means of operating the valve;—the whole being so constructed, arranged and operated as to require practically no physical strength in controlling the operation of the mechanism and enabling the operator to do more and better work in a given time.

My invention is shown in preferred form

employing duplicate interconnected cylinders, in the accompanying drawings, in which—

Figure 1 (Sheet 1), is a side elevation, in section, of a bunching table, showing one of the cylinders and connections, the covers in section, the exhaust chamber and the pedals. The tension springs of the cutters and the cutter guards are omitted. Fig. 2 (Sheet 1), is a front end elevation of the cylinders, front cover in section, the cutter mechanism, with the table in section; and Fig. 3 (Sheet 2), is a plan view of the cylinders and cutting mechanism (enlarged) with a portion of the suction plate.

The table to which my invention is applied, designated by reference letter A in the drawings, to which reference is now made, is of the conventional type, with back and side curbs A¹ and A², respectively, and is supported upon and by a frame E. At the forward edge at the central portion of the table surface is a perforated plate B of convenient size set in flush with the surface of the table and forming the upper wall of a shallow exhaust chamber B¹, connected below with an air exhaust tube B² leading to a suitable exhaust apparatus (not shown) and provided with the usual throttle valve, having an external crank b³ and operating rod b² connecting with a foot pedal b¹.

Mounted upon, and axially parallel with the face of the table and with each other, are two cylinders C, C, connected across at the ends, respectively, by duplicated castings c, c, forming the cylinder heads, which are held from end to end of the cylinders by the tie rods, r. Each of the castings, c, is cored to form a passage c¹ direct from one cylinder to the other. Midway between the cylinders is a pipe c² connecting the end castings and tapping the cross passages c¹,—said pipe c² being interrupted midway by a four-way cock D operated by an external crank d, connected meditately with a foot pedal, p². The cock, D, is entered below by a pipe c³ connecting with a source of compressed air (not shown), and opens at the opposite side at c⁴ to the atmosphere.

The cylinders carry ordinary piston heads (not shown) mounted on piston rods e, e, which extend forward through the usual stuffing boxes in the forward cylinder heads. Each piston rod carries at its forward end a fixed block e¹ upon which is pivotally hung

a yoke e^2 carrying at its lower extremity a disk cutter f , shown in Figs. 1 and 2, but hidden beneath the usual safety guards g shown in Fig. 3. The yoke is carried with a 5 forward inclination and with an adjustable spring s bearing against it midway to give a yielding pressure to the cutting disk f , pivotally mounted at the lower extremity of the yoke. The cutters are carried upon 10 longitudinally adjustable pivot-studs to regulate the width of the cut leaf. I prefer to connect the blocks e^1 across by a tie rod c^3 , which insures a synchronous action of the two pistons as against retarding caused by 15 friction of parts, or otherwise, at one side of the system; but with properly constructed apparatus this is not a necessity.

The operation with respect to placing and smoothing out the leaf by hand on the 20 perforated plate is the same as in any case where a perforated plate and suction are employed. When the leaf is ready placed to be cut, a touch of the foot on the pedal p^2 operating the controlling valve D admits compressed 25 air into the cylinders C at the rear simultaneously and drives the pistons and their disk cutters f forward over the perforated plate B against which they bear with sufficient pressure to cut through the leaf. A 30 similar touch upon the same pedal in the opposite direction opens the rear of the cylinders to the exhaust and admits air pressure to the forward end and withdraws the cutters.

35 All things considered, I find better results in the way of quickness, smoothness and uniformity of action are to be had with duplicate cylinders, thereby giving each cutter its independent motor, rather than with a 40 single cylinder operating a cross head or bar on which both cutters are mounted; and have therefore shown such duplicated structure herein as a preferred form; but it will be obvious that a single cylinder may be used,

and such construction I regard as within the 45 scope of my invention. Other deviations, such for example as the substitution for the piston rod of a reciprocating element driven directly by a rotary instead of reciprocating motor; or a slide valve in place of a rotary 50 valve; etc., may be made. An electromagnetic solenoid may also be used to operate the piston rod without departing from the spirit of my invention.

I claim as my invention and desire to secure by Letters Patent of the United States: 55

1. An improved bunch-maker's table, having in combination a table surface; a reciprocating member; means for driving said member to and fro in a line parallel with the 60 table surface; a yoke-member having one end pivotally carried by the free end of said reciprocating member, said member being inclined to the surface of the table; a rotating disk cutter, carried by the lower end 65 of said yoke member in rolling contact with the table surface; and a spring acting with a yielding adjustable pressure upon the yoke member to maintain a cutting contact.

2. In a bunch maker's table, the combination of a fluid motor embodying a pair of double acting cylinders arranged parallel with each other and with the surface of the table, and reciprocating piston rods; a frame pivotally mounted on the outer ends 75 of said rods; disk cutters on the frame, said frame being mounted at an angle to the vertical; means for holding the cutters in yielding contact with the table surface; and an operating valve for said motor. 80

In testimony whereof I have hereunto set my hand in presence of two subscribing witnesses.

ARTHUR C. PLETZ.
